(57) **CLAIM**

The ornamental design for a see-through sun visor, as shown and described.

DESCRIPTION

FIG. 1 is a perspective view illustrating a see through sun visor.

FIG. 2 is a front view of the see through sun visor shown in FIG. 1;

FIG. 3 is a back view of the see through sun visor shown in FIG. 1;

FIG. 4 is a right view of the see through sun visor shown in FIG. 1;

FIG. 5 is a left view of the see through sun visor shown in FIG. 1;

FIG. 6 is a top view of the see through sun visor shown in FIG. 1; and,

FIG. 7 is a bottom view of the see through sun visor shown in FIG. 1.

The portions of the see through sun visor, shown in broken lines, form no part of the claimed design.

1 Claim, 6 Drawing Sheets
